UNITED STATES PATENT OFFICE

156,719

ORAL INHALATOR

Mack R. Fields, Libertyville, Ill., assignor to Abbott Laboratories, North Chicago, Ill., a corporation of Illinois

Application April 30, 1948, Serial No. 146,072

Term of patent 14 years

(Cl. D83—1)

To all whom it may concern:

Be it known that I, Mack R. Fields, a citizen of the United States, residing at Libertyville, in the county of Lake and State of Illinois, have invented a new, original, and ornamental Design for an Oral Inhalator, of which the following is a specification, reference being had to the accompanying drawing, forming a part thereof.

In the accompanying drawing:

Figure 1 is a perspective view of an oral inhalator embodying my new design;

Figure 2 is a side view of the same device;

Figure 3 is a plan view of the same device;

Figure 4 is an elevation from the front end; and

Figure 5 is an elevation from the rear end.

I claim:

The ornamental design for an oral inhalator, substantially as shown.

MACK R. FIELDS.
